UNITED STATES PATENT OFFICE

141,431

DESIGN FOR A FILM MAGAZINE FOR A PHOTOGRAPHIC CAMERA OR THE LIKE

Jacques Bolsey, New York, N. Y.

Application August 25, 1943, Serial No. 110,993

Term of patent 14 years

(Cl. D61—1)

To all whom it may concern:

Be it known that I, Jacques Bolsey, a former citizen of Russia having first papers of United States citizenship, residing in New York, county of New York and State of New York, have invented a new, original, and ornamental Design for Film Magazines for Photographic Cameras or the like, of which the following is a specification, reference being had to the accompanying drawing forming part thereof in which:

Figure 1 is a side view of a film magazine for

photographic cameras or the like showing my new design,

Figure 2 is a rear view,

Figure 3 is an end view, and

Figure 4 is a front view of the film magazine for photographic cameras or the like shown in Figure 1.

I claim:

The ornamental design for a film magazine for a photographic camera or the like, as shown.

JACQUES BOLSEY.
